US00D342909S

United States Patent [19]

Marchais

[11] Patent Number: Des. 342,909

[45] Date of Patent: ** Jan. 4, 1994

[54] **TEST STATION FOR MONITORING AND
DIAGNOSING OPERATION OF DIESEL
ENGINES**

4,270,174 5/1981 Kaelin et al. .... 324/378 X

[75] Inventor: **Christian Marchais**, Sainville, France

Primary Examiner—Alan P. Douglas
Assistant Examiner—Antoine D. Davis
Attorney, Agent, or Firm—Larson & Taylor

[73] Assignee: **Souriau Diagnostic Electronic**,
France

[57] **CLAIM**

[**] Term: **14 Years**

The ornamental design for a test station for monitoring
and diagnosing operation of diesel engines, as shown
and described.

[21] Appl. No.: **928,199**

DESCRIPTION

[22] Filed: **Aug. 12, 1992**

FIG. 1 is a top, front, left side perspective view of a test
station for monitoring and diagnosing operation of die-
sel engines showing my new design;

[52] U.S. Cl. **D10/75**

FIG. 2 is a top, front, left side perspective view of the
upper portion of the test station, with a keyboard con-
taining drawer extended;

[58] Field of Search 324/77R, 378, 379, 394,
73/117.2; 364/130, 424.1-424.4, 481, 518, 800,
D10/46, 75

FIG. 3 is a left side perspective view thereof;
